AIR CONDITIONING APPARATUS

Rudolf D. Delamere, Toronto, Ontario, Canada,
assignor to Delamere and Williams Limited,
Toronto, Ontario, Canada

Application August 16, 1934, Serial No. 740,053

7 Claims. (Cl. 261—89)

This application relates to apparatus for cleaning and tempering air for ventilation purposes by bringing it into intimate contact with fresh water, and my object is to devise apparatus for this purpose which will effect an efficient multi-stage intimate contact between the water and air without excessive height of apparatus and in which the conditioned air is effectively freed from entrained water as it passes from the apparatus.

5 The invention is hereinafter fully described and illustrated in the accompanying drawings in which

Fig. 1 is a vertical section of the improved apparatus;

15 Fig. 2 a section on the line 2—2 in Fig. 1; and Fig. 3 a section on the line 3—3 in Fig. 1.

In the drawings like numerals of reference indicate corresponding parts in the different figures.

The apparatus as far as its basic features are concerned comprises a casing 1 through which air is caused to flow from the bottom to the top, on its way passing through successive disk shaped sprays of water. The water thrown outwardly in any one spray contacts with the wall of the casing, is collected and led to the axis of the casing to be again thrown out in a spray one step lower and so on.

The treatment is thus in a plurality of stages. As head room is usually limited it is necessary to cut down the height of each stage as much as possible without sacrificing efficiency, and to cut down the resistance to air flow as much as possible. This result is attained by the construction which I will now described.

35 A shaft 6 is vertically journaled in the casing 1 and may be driven in any suitable manner.

To this shaft are secured a series of equally spaced slingers 5 whose function is to throw water in a radial spray outwardly against the 40 casing 1.

Plain disks are not effective as the friction between the water and the disk is not sufficient to cause the water to attain the angular velocity of the disk, and further, the water tends to leave the disk in the form of a sheet and not in the form of a vast number of fine jets.

By putting vanes on a disk it is possible to overcome the first mentioned defect, but it is not possible to put enough vanes on a disk to give a sufficiently large number of fine jets. I overcome the difficulty by forming the slingers as circular bristle brushes, the bristles of each of which are substantially in contact to form a radially ribbed resilient disk which readily imparts a whirling motion to water dropped upon it, and discharges

it in a multitude of fine jets between which the air will flow in fine streams.

The bristles of the slingers may be of organic material or of metal.

Below each slinger an annular trough 3 is secured to the wall of the casing. The inner wall of the trough is eccentric to its outer wall, thus forming an eccentric waterway, widening towards that side of the waterway from which leads the spout 4. Conversely, the waterway of the trough decreases in cross-sectional area each way from the spout 4 which is substantially U shaped in cross-section. The capacity of the trough thus increases near the discharge spout which facilitates flow to the spout. Such a trough allows a maximum space therethrough for the passage of the air, and as the spout adjacent the trough has substantially as great capacity as the trough, friction is kept down to a minimum and the spout need not be inclined downwardly, the hydraulic gradient of the surface of the water being sufficient to effect discharge. Referring to Fig. 1 it will be noted that the top edge of each trough is below its slinger to catch the water thrown thereby and that the bottom of the discharge end of each spout overlies the next slinger so that the water thrown by one slinger is fed to the next slinger. The bottom of the discharge end of each spout is in a plane close to a plane passing through the top edge of the trough to enable the slingers to be spaced as close as possible. The portion of each spout connecting its discharge end with a trough may be inclined to increase the cross-sectional area of the spout so that it will be substantially the same as that of the trough at its point of connection therewith. In other words, the depth and width of the spout at this point will agree with the depth and width of the trough at the point of connection.

It will be seen on reference to Fig. 1 that the inner wall of each trough slopes outwardly from the top to bottom so that water dripping down the wall of a trough is caught by the trough next below and is fed to the corresponding slinger. It should also be noted that while the preferred form for the troughs is to make each trough a circular annulus in plan, other forms are possible whereby the waterway of the trough increases in flow capacity each way from the side opposite the trough.

From the construction and arrangement of the troughs and slingers it follows that the total height of a conditioning stage can be kept down to one-third of what has been previously possible,

thus enabling me to get a sufficient number of stages within the head room usually available. Further it follows from the eccentric design of the water trough that a maximum area of air passage is provided through the trough relative to the liquid flow capacity of the trough.

The casing 1 is supported on a pan 2 which is of greater diameter than the casing so as to catch any water of condensation which may drip from the latter. The lower end of the shaft is secured to the rotor of a pump 10 into which water from the pan 2 may flow.

A pipe 9 connects the outlet of the pump with the inlet 12 leading through the casing above the top trough 3. This inlet might however be directly connected to any outside source of supply.

The pan is provided with an overflow 11. If the pump circulation be employed make-up water may be added to the pan from time to time.

20 Near the top of the casing a fan 8 is secured to the shaft 6. Water laden air passing up to the fan is thrown outwardly against the casing and is then directed inwardly again by the frusto-conical flange 13. An inwardly directed flange 14 is positioned just below the fan blades.

From this it follows that air flowing centrally up the apparatus is thrown outwardly adjacent the top of the apparatus thus losing velocity which gives any water entrained therein the opportunity of dropping out by gravity and being returned to the interior of the apparatus by the flange 14.

The shaft is shown as being driven by the motor 7, the shaft of which carries a pulley 15 belted to the pulley 16 secured to the shaft 6. Obviously other drives might be employed.

It will be distinctly understood that this apparatus may be used for purposes other than conditioning air, for instance it may be used to bring other gases and liquids into intimate contact for various purposes, to separate solids from gases by cleaning the gas or reclaiming the dust, to condense liquids out of gases, to evaporate liquids into gases, to transfer heat from gas to liquid or vice versa, to effect chemical reactions between gas and liquids, or to evaporate one liquid from another liquid without boiling.

What I claim as my invention is:

1. An air conditioning device comprising a casing; a shaft vertically journalled therein; means for causing air to flow through the casing axially thereof; two axially spaced rotary water slingers secured to said shaft; an annular water trough supported against the wall of the casing between the two slingers having an outer circular wall and an inner circular wall eccentric to the outer wall; and a radial spout connected with the trough at its point of greatest width and adapted to discharge onto the lower water slinger, the waterway of the trough decreasing in cross-sectional area each way from a point adjacent the spout and no part of the spout being below the bottom of the trough.

2. An air conditioning device according to

claim 1 in which the capacity of the spout adjacent the trough is at least substantially equal to that of the trough at the same point and its sides substantially parallel.

3. An air conditioning device comprising a casing; a shaft vertically journalled therein; means for causing air to flow through the casing axially thereof; two axially spaced rotary water slingers secured to said shaft; an annular water trough supported against the wall of the casing between the two slingers having an outer circular wall and an inner circular wall eccentric to the outer wall; and a radial U shaped spout connected with the trough at its point of greatest width and adapted to discharge onto the lower water slinger, the bottom of the discharge end of the spout being located above the bottom of the trough, the capacity of the spout adjacent the trough being at least substantially equal to that of the trough at the same point and its sides substantially parallel.

4. An air conditioning device according to claim 1 in which the slingers are formed of their circular bristle-brushes, the bristles of which substantially contact to form radially-ribbed disks having substantially continuous upper surfaces.

5. An air conditioning device comprising a casing; a shaft vertically journalled therein; means for causing air to flow through the casing axially thereof; two axially spaced rotary water slingers secured to said shaft; an annular water trough supported against the wall of the casing between the two slingers; and a radial spout connected with the trough and adapted to discharge onto the lower water slinger, the waterway of the trough decreasing in cross-sectional area each way from a point adjacent the spout and no part of the spout being below the bottom of the trough.

6. An air conditioning device comprising a casing; a shaft vertically journalled therein; means for causing air to flow through the casing axially thereof; two axially spaced rotary water slingers secured to said shaft; an annular water trough supported against the wall of the casing between the two slingers; and a radial U shaped spout connected with the trough and adapted to discharge onto the lower water slinger, the bottom of the discharge end of the spout being located above the bottom of the trough and the capacity of the spout adjacent the trough being at least substantially equal to that of the trough at the same point while no part of the spout lies below the level of the bottom of the trough.

7. An air conditioning device comprising a casing; a shaft vertically journalled therein; means for causing air to flow through the casing axially thereof; two rotary water slingers secured to said shaft, each slinger comprising a thin circular bristle brush, the bristles of which substantially contact to form radially ribbed disks having substantially continuous upper surfaces; and a trough receiving water thrown by one slinger and discharging to the other.
